UNITED STATES PATENT OFFICE

167,134

ELECTRIC LAMP BASE

David Borowitz, Chicago, Ill., assignor to Bradley Manufacturing Company, Chicago, Ill., a corporation of Illinois

Application May 6, 1952, Serial No. 19,618

Term of patent 3½ years

(Cl. D48—20)

To all whom it may concern:

Be it known that I, David Borowitz, a citizen of the United States, and a resident of Chicago, Illinois, have invented a new, original, and ornamental Design for an Electric Lamp Base, of which the following is a specification, reference being had to the accompanying drawing, forming a part thereof.

Figure 1 is a front elevational view of an electric lamp base, embodying my new design.

Figure 2 is a top plan view thereof, the broken lines indicating a standard and socket being omitted for convenience of illustration;

Figure 3 is a right hand end elevational view thereof, the broken lines indicating a standard and socket being omitted for convenience of illustration;

Figure 4 is a rear elevational view thereof, the broken lines indicating a standard and socket being omitted for convenience of illustration;

Figure 5 is a left hand end elevational view

thereof, the broken lines indicating a standard and socket being omitted for convenience of illustration; and

Figure 6 is a bottom plan view thereof, the broken lines indicating a standard and socket being omitted for convenience of illustration.

The dominant features of my present design lie in the portions shown in full lines.

I claim:

The ornamental design for an electric lamp base, substantially as shown and described.

DAVID BOROWITZ.
